UNITED STATES PATENT OFFICE.

CHARLES C. WARREN, OF TOLEDO, OHIO.

DESIGN FOR GROCER'S CAN.

Specification forming part of Design No. 7,761, dated September 15, 1874; application filed June 22, 1874.
[Term of Patent 7 years.]

To all whom it may concern:

Be it known that I, CHARLES C. WARREN, of Toledo, in the county of Lucas and State of Ohio, have invented a new Design for Grocer's Can; and I do hereby declare that the following is a full, clear, and exact description thereof, reference being had to the accompanying drawings, and to the letters of reference marked thereon, which form part of this specification.

The nature of my invention is fully illustrated by the accompanying drawing, to which reference is made.

The body A of the can is made cylindrical in form, with an enlarged base, B. The top D of the can is made with a series of concen-

tric shoulders or offsets, as shown, and surmounted with a ball, G.

The can may be painted in one or more colors, and have any desired words, letters, and figures thereon, and may be ornamented in any desired manner.

What I claim is—

The design for grocer's can, consisting of the cylindrical body A, enlarged base B, top D, and ball G, all as shown and described.

In testimony that I claim the foregoing as my own, I affix my signature in presence of two witnesses.

Witnesses: CHARLES C. WARREN.

T. H. ALEXANDER,
H. M. CLARK.
